CHRISTIAN BEHRENDTS, OF WINNIPEG, MANITOBA, CANADA

LOCK

Application filed September 8, 1930, Serial No. 480,550, and in Canada September 9, 1929.

The invention relates to improvements in locks and an object of the invention is to provide a lock which can be locked or unlocked by the insertion of a special key and which 5 requires no rotary movement of the key to actuate the lock, the interior working parts of the lock being brought to either locked or unlocked position by the simple out and in movement of the key.

10 A further object of the invention is to provide a lock, the interior locking parts of which can be readily shaped to accommodate keys of varying kinds and wherein the key used for any particular lock can be easily and quickly made.

15 A further object of the invention is to provide a lock having relatively few interior parts and those parts designed so that they can be cheaply and quickly constructed and also assembled and mounted within the lock 20 casing.

25 A further object is to construct a lock construction which readily lends itself to the making of various types of locks such as heavy locks or light locks depending on the particular location where the lock is to be used.

30 A further object is to construct the lock so that the locking parts can be readily operated without employing a key from the interior side of the lock and such that said parts can also be retained in locked or unlocked position from the interior side of the lock.

35 With the above more important and other minor objects in view, the invention consists essentially in the arrangement and construction of parts hereinafter more particularly described, reference being had to the accompanying drawings, in which:

40 Fig. 1 is an exterior view of the lock.

45 Fig. 2 is a perspective view of the open end of the lock.

Fig. 3 is a perspective view of the locking plate.

50 Fig. 4 is an enlarged detailed horizontal sectional view at 4—4 Figure 1.

Fig. 5 is a vertical sectional view at 5—5 Figure 4 and showing the lock in locked position.

55 Fig. 6 is a view similar to Figure 5 and showing the lock in unlocked position.

Fig. 7 is a vertical cross sectional view at 7—7 Figure 4 and showing the parts in locked position.

Fig. 8 is a view similar to Figure 7 and showing the parts in unlocked position. 55

Fig. 9 is a vertical cross sectional view at 9—9 Figure 6 and showing the key inserted.

Fig. 10 is a cross sectional view at 10—10 Figure 5.

Fig. 11, 12, 13 and 14 are side views of the 60 several locking latches employed.

Fig. 15 is an interior view of a modified type of lock in the locked position.

Fig. 16 is an interior view of the latter lock 65 in the unlocked position with the key inserted.

In the drawings like characters of reference indicate corresponding parts in the several figures.

The lock casing 1 is substantially rectangular and is herein shown as formed from inner 70 and outer plates 2 and 3, the flanged top and bottom plates 4 and 5 riveted thereto and a pair of vertically disposed lengthwise extending parallel guide plates 6 and 7 flanged at their upper and lower edges and fastened permanently to the top and bottom plates. The plates 4, 5, 6 and 7 provide an interior substantially rectangular compartment 8 which contains the locking latches shortly described. 75

The front end of the casing is closed by a substantially rectangular block 9 which is provided with a centrally located vertical slot 10 continuous with the adjacent end of the cavity 8 and two centrally located and opposing cross slots 11 and 12 communicating with the vertical slot. A channel-shaped guard plate 13 encloses the block being fastened by side screws 14 to the casing and the guard plate is provided with a centrally located transverse slot 15 registering with the slots 11 and 12. The casing is suitably fastened such as by morticing in the swinging or free side of a door 16, the guard plate being flush with the edge of the door. 80

To the door frame 17 in a location directly opposite the centre of the lock, I fasten permanently a locking plate 18 which is provided with a pair of similar right and left somewhat wedge-shaped lugs 19 and 20 having the narrow ends turned outwardly and the heel por- 95

tions 21 thereof spaced apart a distance approximately equal to the width of the slot 10. The lugs are adapted to enter or withdraw from the slots 11 and 12 when the door is closed or opened and when the door is in the closed position, the space between the butt ends 21 of the lugs is directly opposite the forward end of the cavity 8.

Within the cavity 8, I place a plurality of similarly constructed locking latches, four of such latches indicated at 22, 23, 24 and 25 being herein used. The latches are all pivotally mounted side by side within the cavity 8 on a cross pin 26 carried by the inner plates 6 and 7, the pin being at the end of the lock remote from the edge of the door. The length of the latches is such that their free ends operate in the vertical slot 10.

Each latch is provided adjoining the pin with a substantially square opening 27 and towards the end remote from the pin with a further relatively large opening 28 and between these openings at one side with a relatively large slot 29, the inner end of which is provided with a semicircular notch 30, the notch being centered on the longitudinal axis of the latch. It will be observed that the notches 30 of the latches 22 and 24 are at the same sides of the latches while those of the latches 23 and 25 are at the opposite sides, the reason of which will be later apparent. The free ends of the latches are provided with escape slots 31 positioned relatively in the several latches as clearly shown in Figures 11, 12, 13 and 14. The right hand side of each of the openings 28 is provided with a pair of slots 32 but it will be observed that the slots of the pairs are not all spaced an equal distance apart.

In placing the latches in the cavity 8, the latch 25 is put in first, then the latches 24, 23 and 22 in the order named so that the latch 22 is nearest the observer in the section shown in Figure 5. The latches when inserted are free to move up and down between the plates 6 and 7 turning on the pin 26 and the free ends thereof having the slots 31 therein are operating within the vertical slot 10 and here I might mention that the slots 31 are complementary to the slots 11 and 12.

In order that the inner pair of latches may have a bearing against the block 9, I have provided them each with out turned end flanges 33 which engage the side faces of the slot 10 when the lock is unlocked and which also engage the heels 21 of the lugs 19 and 20 when the lock is locked. It will be observed in Figure 6 that if the latches be shifted so that the slots 31 are all in registration, the door can be opened as the lugs 19 and 20 can at such time clear through the slots 11 and 12 and that if the said slots are not in registration as shown in Figure 5, the ends of the latches positively prevent the

opening of the door as they are caught between the heels of the lugs 19 and 20.

The in swung position of the latches is limited by a cross pin 34 carried by the plates 6 and 7 and when the latches are in their locking position, the notches 30 receive the latter pin in the manner best shown in Figure 5 and here it will be observed that the latter pin holds the latches sufficiently apart to provide a key hole opening 35 therebetween. The latches are normally pressed to the position shown in Figure 5 by U-shaped springs 36, two springs being utilized, one end of each spring being attached to one latch and the other end of the same spring being attached to the next adjacent latch. The outer plate 3 of the casing and the inner plates 6 and 7 are provided with horizontally aligned vertically disposed key hole slots 37 and the key passage 35 is located between the key hole slots of the inner plates.

The key 38 used is of the irregular shape shown in Figure 9 and it will be observed that it has a pointed end 39. When the key is inserted in the slot 37 and pushed inwardly into the lock, the pointed end 39 thereof enters the passage 35 and as the key goes in, the latches are all actuated thereby a greater or less amount depending on the shape of the key. In the final inserted position of the key, such being limited by the stop shoulder 40 thereof, the slots 31 are all in registration as shown in Figure 6 and in such position, the door is free to open as the latches can at such time clear past either of the lugs 19 or 20. When the key is subsequently withdrawn, the springs return the latches to their initial position as shown in Figure 5. Accordingly when the door is closed and the key is withdrawn, the latches become automatically locked between the heels of the lugs 19 and 20.

By varying the positions of the notches 31 in respect to the longitudinal axis of the latches, I vary the distances which the latches have to be shifted to come into registration and accordingly it is an easy matter to make locks which can be opened by various shapes of keys. The inserted key, however, must bring all the notches 31 into registration to permit the door to open.

In order that the latches may be moved to unlocked position from the interior side of the lock, I have provided a pair of finger grips 41 and 42 at the inner side of the lock, these being formed at the outer ends of a pair of jaws 43 and 44 pivotally carried by pins 45 supported by a substantially square bearing frame 46 secured to the plate 2. The jaws are tapered as best shown in Figures 7 and 8 and pass through the openings 27 of the latches and have their inner ends entered in an opening 47 provided in the plate 6.

The arrangement of the jaws and the openings 27 is such that when the jaws are in

the closed position as shown in Figure 7, the slots 31 of the latches are in their locked position and that when the jaws are fully opened as shown in Figure 8, the slots 31 are in registration. The opening position of the jaws is limited by the opening 47.

In order that one may fasten the latches either in their locked or unlocked positions and from the interior of the lock, I have provided a locking lever 48 pivotally carried by the inner plate 2 and provided at its inner end with a blade 49 which is adapted to enter selected slots 32 of the latches when the latter are in their locked or unlocked positions. In this connection, I may point out that the slots 32 are arranged so that when the latches are in their locked position, certain of the slots will be aligned to receive the blade and that when the latches are in their unlocked position, certain other of said slots will be in alignment to receive the blade.

As before stated, the latches are normally pressed to locked position by the springs and are spread to open or unlocked position by either the manipulation of the jaws or the insertion of the key. Accordingly when the door is open, the latches are in their locked position unless fastened in their unlocked position by the lever 48. When the door is closed and assuming the blade 49 is not in the notches 32, the pointed end of the lug 19 or the lug 20, depending on which direction the door swings, is adapted to pass through the slot 11 or the slot 12 and enter the entrance passage reserved at 50 Figure 5 to receive it and as the door closes, the lug forces the latches apart against the action of the springs, the latches so escaping over the lug and finally taking their locked position between the butt ends of the lugs.

The door will accordingly be locked closed automatically and can only be opened from the exterior by the key and from the interior by the pressing together of the finger grips 41 and 42.

From the above it will be apparent that the lock can be manufactured at relatively small cost and the parts easily and quickly assembled and that the latch structure can be readily modified to be actuated by various shapes of keys and that only one key will fit any particular lock as any variation in the shape of the key will not pass the slots 31 into registration and position them in respect to the butt ends of the lugs 19 and 20 such that the door can be opened.

In Figures 15 and 16, I have shown a simple type of lock operated by the insertion of a key, the shape of the key being such that the in movement thereof actuates the locking latches. In the type of lock previously described, the locking latches are pivoted on the pivot pin but in this type of lock, the locking latches 51 are slidably mounted side by side between the front end 52 of the lock casing

and an interior guide plate 53. The casing is provided with an entrance slot 54 for a hasp in the form of an eye (not shown) and each of the locking plates is provided with a vertical slot 55 and a horizontal slot 56 opening to the same and the slots provide catches 57 which when the locking latches are in their unlocked position as shown in Figure 16, permit of the insertion of the eye through the slot 54 and when the latches are in their locked position as shown in Figure 15, engage the eye, the catches 57 entering the same.

The several latches are provided with strikers 58 which are adapted to be spread apart by the insertion of the key 59, the key as it moves in, endwise shifting all the latches and bringing the same to the position shown in Figure 16 which is the unlocked position of the catches 57. Springs 60 are mounted within the casing and engage the opposite ends of the latches and hold them normally in their locked positions as shown in Figure 15.

I have not given a very detailed description of the modified type of latch shown in Figures 15 and 16 as the structure therein disclosed is only to show that instead of constructing the lock with the latches pivoted, it is possible to construct it with the latches so that they end shift, being end shifted by the in pushing of the key and being brought to their unlocked position by the key, the peculiar shape of which controls the shifted position of the several latches.

What I claim as my invention is:—

1. A key operated lock comprising a casing, a plurality of similar latches arranged side by side within the casing, said latches being exposed at one end beyond the casing and being provided at such ends with differently positioned slots, a pivot pin pivotally supporting the other ends of the latches, springs engaging the latches and normally pressing the same inwardly to place the slots out of registration, a stop pin carried by the casing and passing through suitable slots provided in the bodies of the latches and limiting the in swung position of the latches under the influence of the springs, and a locking lever carried by the casing and engageable with the latches to lock the same with the end slots out of or in registration as desired.

2. A key operated lock comprising a casing, a plurality of similar locking latches positioned side by side within the casing, said latches being exposed at one end beyond the casing and being provided at that end with differently positioned slots, a pivot pin pivotally supporting the other ends of the latches, spring means engaging the latches and normally holding the same against spreading, a stop pin passing through the

latches and limiting their closed position under the action of the springs, finger actuated means operable from the interior side of the casing for spreading the latches to bring the end slots thereof into registration and finger actuated means operable from the interior side of the casing for locking the latches in or out of registration as desired.

Signed at Winnipeg this 14th day of August, 1930.
